UNITED STATES PATENT OFFICE.

JOHN J. TYNE, OF CHICAGO, ILLINOIS.

WATER-COMMINGLING HEAD.

1,030,144.

Specification of Letters Patent. Patented June 18, 1912.

Application filed February 9, 1912. Serial No. 676,613.

To all whom it may concern:

Be it known that I, JOHN J. TYNE, a citizen of the United States of America, and a resident of Chicago, in the county of Cook, 5 State of Illinois, have invented certain new and useful Improvements in Water-Commingling Heads, of which the following is a specification.

This invention relates to hot and cold 10 water commingling heads for bath tubs in which the commingling action takes place before a discharge is had into the tub. And the present improvement has for its object to provide a simple and efficient structural 15 formation of a commingling head in which the commingling is insured in a thorough manner, and with which ready connection is afforded for the branch hose or pipe by which the ordinary shower bath attachments 20 of bath tubs are supplied, all as will hereinafter more fully appear.

In the accompanying drawings: Figure 1, 25 is a detail end elevation of the present commingling head and its supply connections, a portion of a bath tub being shown in dotted lines. Fig. 2, is a detail longitudinal section on line $x-x$, Fig. 1, of an end portion of a bath tub with the present improvement in place. Fig. 3, is a detail section of 30 the commingling head, on line $x'-x'$, Fig. 1.

Similar reference numerals indicate like parts in the several views.

Referring to the drawings, 1 represents the single piece main body of the commingling head, formed with an elongated 35 horizontal commingling chamber 2, the various walls of which are integrally formed by the casing of said body as shown.

3 and 4 are inlet orifices formed in in- 40 turned necks 5 on the back wall 6 of the head 1, in adjacent relation to and communicating with the respective ends of the elongated horizontal chamber 2, aforesaid. Said inlet orifices 3 and 4 are screw-threaded 45 for the attachment of the hot and cold water supply pipes hereinafter described.

7 is a discharge neck integrally formed on the front wall 8 of the head 1 and located centrally thereon approximately equidistant 50 between the aforesaid inlet orifices 3 and 4. In the present construction the discharge neck 7 is arranged in a plane forward of the main body 1 and depends a distance below the same so that when the commingling 55 head is secured in place upon the inner face

of a vertical wall of the bath tub, as shown in Fig. 2, ample clearance will be provided at the rear of said neck, in the operation of coupling thereto the flexible hose of an ordinary shower bath attachment or the like. 60 And with a view to facilitate said coupling operation the lower end of the discharge neck 7 will be exteriorly corrugated as shown.

9 and 10 are hot and cold water branch 65 pipes passing through orifices formed therefor in a vertical wall of the bath tub and screwed into the screw-threaded necks 5 of the back wall 6, of the head 1, before described.

11 and 12 are holding nuts screwing upon the branch pipes 9 and 10 and having bearing against the exterior of the vertical wall of the bath tub above mentioned, so that as said nuts are screwed to place the head 1 will 75 be drawn tightly against the inner face of said wall and securely held in place.

13 and 14, are the vertically arranged main hot and cold water supply pipes, provided with individual controlling valves 15 80 and 16, the valve stems of which extend up through openings formed therefor in the top rim or roll of the bath tub so as to be convenient for operation. The pipes 13 and 14 are individually coupled to the branch 85 pipes 9 and 10 aforesaid, by the usual coupling means, as illustrated in the drawings.

Having thus fully described my said invention what I claim as new and desire to secure by Letters Patent, is:—

In a commingling head for bath tubs, a single piece head formed with an elongated horizontal chamber, a pair of inlet orifices in inturned necks on the rear wall of said chamber adjacent to the ends thereof, and a 95 depending discharge neck arranged centrally of the head and in a plane forward of the main body of the head, a pair of branch supply pipes adapted to pass through orifices in a vertical wall of a bath tub and 100 screw into said orifices, and holding nuts mounted on said branch pipes, substantially as set forth.

Signed at Chicago, Illinois this 7th day of February 1912.

JOHN J. TYNE.
